UNITED STATES PATENT OFFICE.

CHARLES W. TURNBULL AND JOHN HENRY FOX, OF ALBERT LEA, MINNESOTA.

VAPOR OIL-BURNER.

1,340,038.

Specification of Letters Patent.

Patented May 11, 1920.

Application filed October 29, 1919. Serial No. 334,138.

To all whom it may concern:

Be it known that we, CHARLES W. TURNBULL and JOHN H. FOX, citizens of the United States, residing at Albert Lea, in 5 the county of Freeborn and State of Minnesota, have invented certain new and useful Improvements in Vapor Oil-Burners; and we do hereby declare the following to be a full, clear, and exact description of the invention, such as will enable others skilled 10 in the art to which it appertains to make and use the same.

The present invention relates to improvements in vapor oil burners, and has for 15 an object to provide an improved vapor oil burner adapted to volatilize the fuel more efficiently and deliver the fuel to the burner under pressure, whereby the ignitable contents of the fuel are more thoroughly 20 burned and a correspondingly more intense flame produced.

The invention also provides an improved 25 valve for use in connection with the improved vapor oil burner, and which consists in the constructions, combinations and arrangements hereinafter more fully described and claimed.

In the accompanying drawings forming 30 a part of this application, and in which similar reference symbols indicate corresponding parts in the several views:

Figure 1 is a plan view of an improved vapor oil burner constructed in accordance with the present invention.

Fig. 2 is a side view of the same.

Fig. 3 is a vertical sectional view of the improved burner.

Fig. 4 is a plan view of the improved valve.

Fig. 5 is a front view of the same with the parts shown in section.

Fig. 6 is a horizontal sectional view of the same; and

Fig. 7 is a longitudinal sectional view 45 through one of the burners.

Referring more particularly to the drawings, 1 designates a base of suitable construction, preferably an elongated relatively narrow bar having a cross piece 2 at one end thereof and formed at its other end into a wide generating pan 3.

A generating coil 4 is situated above the pan 3 and connects with a vaporizing coil 5 which is supported on the base 1, and has

at its inner end a perforated lug 6 for the 55 passage of a screw or other fastening 7 adapted to take into a threaded opening in the cross piece 2.

The inner end of the vaporizing coil 5 is connected to one end of a vapor cylinder 8 60 which is of large dimensions and which extends longitudinally of the burner above and substantially parallel with the base 1.

A T coupling 9 is connected to the other end of the vapor cylinder 8, and is adapted 65 to receive other couplings 10 and 11 which carry the two burners 12 and 13.

At 14 is shown the improved combination valve for controlling the passage of the fluid.

The generating pan 3, base 1, and cross piece 2 are preferably all formed in the same casting, together with a standard 15 which rises out of the pan 3 to support the forward end of the vapor cylinder 8.

Referring more particularly to Fig. 7, 11 represents the T above referred to, which is threaded at opposite ends so that the threaded rear end of the burner nozzle 13 may be screwed into one end of such T 11. 80 The opposite end of the T 11 is adapted to receive a plug 16 which is threaded and screwed therein, the plug having a reduced end 17 also screw threaded to receive a packing nut 18. A needle valve is shown at 19 85 and passes through the plug 16, T 11, and burner nozzle 13, and is adapted to regulate the flow of the fuel through the open end of said nozzle 13. The valve 19 has a bent end 20 by which it may be grasped and 90 manipulated. By moving the needle 19 back and forth the orifice 21 of the burner or torch may be kept clear.

The two torches or burners 12 and 13 are arranged to direct their respective flames at 95 opposite sides of the vapor cylinder 8 and above the vaporizing coil 5, so that the cylinder and coil are heated and cause the proper vaporization of the fuel before it is allowed to pass out through the torches.

The inner end of the vaporizing coil 5 is provided with a screw threaded opening 22 into which a vertically disposed nipple 23 is screwed, and which in turn is screwed into a right angularly disposed end 24 of 105 the vapor cylinder 8.

The opposite end of the vapor cylinder 8 is also internally screw threaded to receive

a nipple 25 to which the T 9 connects, and a strap 26 passes about the nipple 25 and T 9 and connects to the standard 15 for the purpose of holding these parts in the elevated 5 position shown.

Referring more particularly to Figs. 4, 5 and 6, 27 is a threaded shank of the valve casing which is provided with an oil duct 28 and an air passage 29. This 10 shank 27 is adapted to be screwed into the usual pressure tank. The oil passage 28 connects with an outlet 30 and is under the control of a valve 31, by which the quantity of oil can be regulated. The 15 air passage 29 also connects with the outlet 30 through a transverse passage 32, the air being under the control of a valve 33. The pressure gage 34 is in communication with the air passage 29 and shows the condition 20 of the air pressure source.

The oil duct 28 also has a normally closed outlet 35 extending vertically downward and which is under the control of a valve 36. The outlet 35 connects to a pipe 37 of 25 very small diameter, known as the generating feed wire. This generating feed wire, as shown in Figs. 2 and 3, extends into the generating pan 3 and is adapted to deliver a quantity of the oil thereto when the apparatus 30 is in cold condition and is to be started. After the delivery of a predetermined amount of oil to the generating pan 3, a match is applied, igniting the oil which heats the generating coil 4 and vaporizes 35 the fuel therein.

The feed wire 37 is provided with a conical end 38 adapted to fit in a correspondingly formed socket in the lower end of the outlet 35, and a nut 39 surrounds the feed wire 40 37 and is adapted to screw into the outlet 35.

The valve casing is also provided with an inlet 40, for air under pressure, which is governed by a valve 41.

The outlet 30 of the valve casing is connected by a pipe of small diameter or feed wire 42 which is joined to the outlet 30 in any suitable manner, and at its opposite end connects with the generating coil 4, as shown in Fig. 6. Any suitable connection may be 50 used for this purpose.

The oil from the pressure tank enters directly through the duct 28 and passes in controlled quantity into and through the outlet 30 to the feed wire 42 and generating coil 4, where it becomes heated and afterward passes to the vaporizing coil 5 where it is further heated and vaporized, the vapor ascending into the vapor pressure cylinder 8, where it is collected in large quantities before issuing through the burners or torches 55 12 and 13.

When it is desired to clean the various coils and pipes, the valve 33 may be opened wide to allow air under pressure to pass 60 through the transverse passage 32 and

through the outlet 30 to the several coils and through the vapor pressure cylinder to the torches.

It is obvious that those skilled in the art may vary the details of construction and arrangements of parts without departing from the spirit of our invention, and therefore we do not wish to be limited to such features except as may be required by the claims. 70

We claim:

1. An improved vapor oil burner including a base provided with a generating pan, a generating coil above the pan in communication with a fuel supply, a vaporizing coil supported on said base and connected to said generating coil, a vapor pressure cylinder connected at one end to the delivery end of said vaporizing coil and lying above said coils, and a burner connected to said cylinder, substantially as described. 75

2. An improved vapor oil burner including a base provided with a generating pan, a generating coil above the pan in communication with a fuel supply, a vaporizing coil supported on said base and connected to said generating coil, a vapor pressure cylinder connected at one end to the delivery end of said vaporizing coil and lying above said coils, and a pair of torches connected at opposite sides of said cylinder and in communication with the cylinder, substantially as described. 85

3. An improved vapor oil burner including a base provided with a generating pan, a generating coil above the pan in communication with a fuel supply, a vaporizing coil supported on said base and connected to said generating coil, a vapor pressure cylinder connected at one end to the delivery end of said vaporizing coil and lying above said coils, and a pair of torches, one at each side of said cylinder and in communication therewith, said torches adapted to direct their flames along opposite sides of said cylinder and above said coils, substantially as described. 100

4. An improved vapor oil burner comprising a base having a generating pan, a generating coil supported above the pan, a connection between said coil and oil supply, a valve for controlling said oil supply and also arranged to deliver oil to said generating pan, a vaporizing coil connected to said generating coil, a vapor pressure cylinder connected to said vaporizing coil and lying above said coils, and a torch in communication with said vapor pressure cylinder, substantially as described. 105 115

5. An improved vapor oil burner including a base having a generating pan, a generating coil above the pan arranged in controlled communication with a source of fuel supply, a vaporizing coil connected to said generating coil, a vapor pressure cylinder lying above said coils and connected to said 120 125 130

vaporizing coil at one end thereof, a torch connected to the other end of said cylinder said torch including a coupling piece, a nozzle removably carried at one end of said 5 coupling piece and having a discharge orifice, a plug connected to the other end of said coupling piece, and a clean-out needle mounted for longitudinal movement through said plug, coupling piece and nozzle and having one end adapted to engage 10 through the discharge orifice, with means whereby said needle may be manipulated, substantially as described.

6. An improved vapor oil burner includ- 15 ing a base, a generating pan formed at one end of said base, a generating coil above the the generating pan and in communication with an oil supply, a vaporizing coil of larger diameter than said generating coil 20 and connected to the latter and supported on said base, a vapor pressure chamber of comparatively large diameter connected to the inner end of said vaporizing coil and lying above said coils, and a torch connected 25 to said chamber, substantially as described.

7. An improved vapor oil burner includ- 30 ing a base, a generating pan at one end of said base, a generating coil above said pan, a connection placing said coil in commun- cation with a source of oil supply, a valve in said connection, said valve having a con-

trolled oil supply and a controlled air supply in communication with said generating coil, means whereby a controlled quantity of oil may be delivered to said generating 35 pan, and a controlled inlet for air under pressure to said valve, a vaporizing coil connected to said generating coil, a vapor pressure chamber above said coils and connected to said vaporizing coil, and a torch 40 in communication with said chamber, substantially as described.

8. An improved vapor oil burner includ- 45 ing a base, a generating pan at one end of said base, a cross piece at the other end of the base, a generating coil above said pan in communication with a source of oil supply, a vaporizing coil having its convolutions supported by said cross piece and having its inner end secured thereto, the inner 50 end of said vaporizing coil having an upwardly opening outlet, a pressure cylinder having a down turned end in communication with the outlet of said vaporizing coil, a standard adapted to support the forward 55 end of said cylinder, and a pair of torches at opposite sides of said cylinder and in communication therewith for directing their flames above said coils, substantially as described.

CHARLES W. TURNBULL.
JOHN HENRY FOX.
